UNITED STATES PATENT OFFICE.

FRANK H. WALKER, OF CHICAGO, ILLINOIS, ASSIGNOR OF ONE-HALF TO SAMUEL H. GILBERT, OF CHICAGO, ILLINOIS.

STARTER.

1,355,630.

Specification of Letters Patent. Patented Oct. 12, 1920.

Application filed November 20, 1916. Serial No. 132,282.

To all whom it may concern:

Be it known that I, FRANK H. WALKER, a citizen of the United States, residing at Chicago, in the county of Cook and State 5 of Illinois, have invented a certain new and useful Improvement in Starters, of which the following is a specification.

My invention relates to improvements in starting mechanisms for internal combustion 10 motors and the like. It has for one object to provide a new and improved form of starter which will be self-contained, positive in its operation, simple and convenient in its control which will not add appreciably either to the weight or bulkiness of the 15 motor and which can easily and conveniently be applied to automobiles and the like. Other objects of my invention will appear from time to time in the specification.

My invention is illustrated more or less 20 diagrammatically in the accompanying drawings, wherein—

Figure 1 is a longitudinal section on an 25 enlarged scale through the starting cylinder;

Fig. 2 is a similar section through a modified form of starting cylinder.

Like parts are indicated by like letters in all of the figures.

E is an automobile starting cylinder 30 adapted to be mounted on an automobile frame, not shown, closed at one end by a cap E¹ anchored to the frame by a coupling, not shown. It is closed at the other end by

35 a cap E³. This cap contains an enlarged cylinder like bearing portion E⁴. This is contained within a housing E⁵, which housing terminates in a guide sleeve E⁶ closed by means of a stuffing box E⁷ which permits

40 the passage of the piston rod D¹². The opposite end of the rod D¹² is terminated by a coupling screw-threaded thereto, D¹¹, to which is attached a wire cable or any other suitable connecting means adapted to transmit motion from the rod D¹² to the shaft

45 of the automobile engine not shown, to rotate it. The piston rod D¹² terminates in a plunger E⁸ slidable in the chamber E⁴, and this plunger E⁸ which is also a piston rod, 50 carries the piston E⁹. This piston is rigidly attached thereto being in screw-threaded

engagement therewith and held in locked position by means of a nut E¹⁰. This piston E⁹ is slidable in the cylinder E. E¹¹ is a feed pipe discharging through a check valve 55 E¹² into a passage E¹³ in the wall of the housing E⁵ through which carbureted air under pressure is forced from a source not shown. This passage extends through the wall of the housing communicating with the cylinder E⁴ and also a passage E¹⁴ communicating with the cylinder E⁴ in opposition to the passage E¹³, and passing through the wall of the housing E⁵ to a chamber E¹⁵, which chamber is in communication with 60 the cylinder E. The passage E¹⁶ leads from the cylinder E⁴ to a spark plug E¹⁷, but this passage is closed by the plunger E⁸ until it has been withdrawn toward the right far enough for the left hand end of the plunger 65 to pass beyond the opening of the passage E¹⁶.

F is a false piston mounted on the piston E⁹. F¹ is a wiping and stuffing or packing ring in engagement with the wall of the cylinder E and contained partially between the false piston F and the piston E⁹ and projecting outwardly from them toward and in close engagement with the cylinder wall. This false piston is held on the piston 70 E⁹ by any suitable means not here shown. F² is a passage leading through the false piston F into the chamber F³ in the interior of that piston and closed on one side by the piston E⁹. This passage communicates at 75 its other end with the far end of the cylinder E. F¹³ is a valve closing the passage F². It is mounted on a stem F⁴ to be slidable in the false piston and the main piston and which projects beyond them. F⁵ is a 80 pocket in the front wall of the main piston E⁹ adapted to contain the valve when in the unseated position. The pin F⁶ is adapted as the piston moves toward the right to strike the cap E¹, whereas as the piston 85 moves toward the left, to strike the cap E³.

In Fig. 2 I have illustrated a modified form of cylinder. The cylinder G is closed at one end by the cap G¹ which cap carries a control cylinder G³ and terminates in a 90 guide sleeve G⁴. G⁶ in this case is a piston rod, and it extends clear through to carry 100

the piston G⁷. Intermediate the ends of the rod, however, is a small sub-piston G⁸, slideable in the smaller cylinder G³. G⁹ is a supply passage. It communicates only with the outer end of the cylinder G³ and the only passage between is the passage G⁶, and the driving pressure on the piston G⁷ is through the cylinder G³. G¹⁰ is a passage leading from a point intermediate the two ends of the main cylinder G through a spark plug G¹¹ so that the spark plug is not exposed until the piston G⁷ has passed down a considerable portion of its stroke.

M is a release port arranged near the end of the piston travel in the starting cylinder for the purpose of releasing the pressure on the back side of the piston, and finally causing the entrapment of a certain amount of air in the end of the cylinder to cushion the piston.

The use and operation of my invention are as follows:

While the engine is operating in the usual manner, the sparks are fired, and the supply of combustible mixture is fed into the engine in the normal way. The compressor will operate to store air under pressure in the tank and this compressor may be controlled in any suitable manner not shown.

When the operator wishes to start the engine, he opens the valve and permits air under pressure to flow in from the storage tank through the piping to the carburetor where it is mixed with a sufficient quantity of liquid combustible to make it explosive. This carbureted mixture under pressure then flows into the starting cylinder, gradually forcing the piston back, thus slightly rotating the clutch sleeve so that the clutch teeth may come gradually into engagement.

This gradual movement of the piston continues until the plunger moves back far enough to uncover the channel leading to the spark plug. The spark plug will meanwhile have been excited, and when the charge comes in contact with the spark it will be exploded and the piston will then be violently forced to the rear by the pressure of the explosion. This will rotate the engine crank shaft one or more times as the case may be, the air on the back side of the piston escaping through the open port as shown. The piston finally closes this port and traps a certain amount of air in the end of the cylinder, which air is compressed to cushion the piston at the end of its stroke. When the pin on the piston strikes the cap, it opens the valve and throws it back into the previous position in the pocket as shown. This permits the gas to escape from the working side of the piston through the cylinder receiving the pressure and permits the return spring to operate to draw the parts back into the position shown in the drawings. The fact that the release

valve is contained in the pocket prevents its being picked up by the outflow of air and assures that the passage would stay open until the piston had returned to its initial position when the pin strikes the wall of the cap and the valve is again ready for the next operation.

I claim:

1. A self-starting device for explosive engines comprising a subsidiary cylinder and a piston slideable therein, means for supplying a combustible charge thereto, under a pressure, to start the movement of the piston, and means for subsequently igniting the charge to increase the driving pressure upon the piston, said means comprising an ignition device, a communication between this and the interior of the cylinder and means directly responsive to the movement of the piston for opening such communication to permit the combustible charge to reach the ignition device.

2. A self-starting device for explosive engines comprising a subsidiary cylinder, a piston slideable therein, means for supplying an explosive charge under pressure thereto and means for igniting such charge after the piston has commenced its travel under the influence of the pressure under which the charge is supplied, said means comprising an ignition source, a closed communication between it and the cylinder, and means directly responsive to the movement of the piston for opening such communication.

3. A self-starting device for explosive engines comprising a subsidiary cylinder, a piston slideable therein, means for supplying an explosive charge under pressure thereto and means for igniting such charge after the piston has commenced its travel under the influence of the pressure under which the charge is supplied, said means comprising an ignition source, a closed communication between it and the cylinder, and means responsive to the movement of the piston for opening such communication, said means comprising a plunger carried by the piston and adapted normally to close the communication with the ignition means.

4. A self-starting device for explosive engines comprising a subsidiary cylinder, a piston slideable therein, means for supplying an explosive charge under pressure thereto, an ignition chamber, a spark plug contained therein, means for exciting the spark plug, a connection between such chamber and the cylinder, and means carried by the piston for normally interrupting such connection.

5. A self-starting device for explosive engines comprising a subsidiary cylinder, a piston slideable therein, means for supplying an explosive charge under pressure thereto, an ignition chamber, a spark plug

- contained therein, means for exciting the spark plug, a connection between such chamber and the cylinder, and means carried by the piston for normally interrupting such connection, the relative arrangement of piston, piston travel and piston carried means being such that the interrupting means become inoperative before the piston reaches the end of its travel.
10. The combination with a cylinder and piston slidable therein of a cap closing one end of the cylinder, an enlarged hollow barrel carried by said cap, a plunger mounted on the cylinder and slidable within such barrel, and a piston rod projecting outwardly from the end of such plunger, means for admitting a combustible fluid under pressure to the interior of such barrel, at the end of the plunger removed from the piston, a passage contained within the cap leading from such end of the barrel to the cylinder, an ignition chamber and a passage leading from it to the cylinder, a spark plug in the ignition chamber, such passage being closed by the plunger, the plunger being shorter than the total piston travel.
7. The combination with a cylinder and piston slidable therein of a closed cap for one end of the cylinder, a cap at the other end of the cylinder, and a piston rod extending out through it, means for exerting a pressure upon the piston rod side of the piston, a valve in the piston normally closed, a pocket in which the valve is contained when open, means projecting beyond the piston adapted to engage the closed cap to open the valve when the piston reaches the end of its excursion.
8. The combination with a cylinder and piston slidable therein of a closed cap for one end of the cylinder, a cap at the other end of the cylinder, and a piston rod extending out through it, means for exerting a pressure upon the piston rod side of the piston, a valve in the piston normally closed, means projecting beyond the piston adapted to engage the closed cap to open the valve when the piston reaches the end of its excursion, a port in the cylinder wall adjacent the closed cap adapted to be closed by the piston, substantially at the end of its excursion toward the cap.
9. The combination with a cylinder and piston slidable therein of a closed cap for one end of the cylinder, a cap at the other end of the cylinder, and a piston rod extending out through it, means for exerting a pressure upon the piston rod side of the piston, a valve in the piston normally closed, means projecting beyond the piston adapted to engage the closed cap to open the valve when the piston reaches the end of its excursion, a pocket in which the valve is adapted to be contained, with protective means for preventing direct contact with

the gases as they rush out from the pressure side of the cylinder through the valve controlled apertures.

10. The combination with a cylinder and a piston slidable therein of a sub-cylinder of smaller cross-section than in the main cylinder, a piston rod extending from the piston out through the sub-cylinder and a small piston carried by the rod, means for introducing a combustible gas under pressure into the sub-cylinder upon that side of the sub-piston farthest removed from the main piston, means for continuing the introduction of such gas as the piston moves back, ignition means located in the wall of the main cylinder adapted to be closed by the piston until it has made a portion of its travel.

11. The combination with a cylinder and piston slidable therein of a closed cap for one end of the cylinder, a cap at the other end of the cylinder, and a piston rod extending out through it, means for exerting a pressure upon the piston rod side of the piston, a closed chamber within the piston, a valve in the piston chamber normally closed, means projecting beyond the piston adapted to engage the closed cap to open the valve when the piston reaches the end of its excursion.

12. The combination with a cylinder and piston slidable therein of a closed cap for one end of the cylinder, a cap at the other end of the cylinder, and a piston rod extending out through it, means for exerting a pressure upon the piston rod side of the piston, a closed chamber within the piston, a valve in the piston chamber normally closed, means adapted to open the valve when the piston reaches the end of its excursion.

13. The combination with a cylinder and piston slidable therein of a closed cap for one end of the cylinder, a cap at the other end of the cylinder, and a piston rod extending out through it, means for exerting a pressure upon the piston rod side of the piston, a closed chamber within the piston, a valve in the piston chamber normally closed, means projecting beyond the piston adapted to engage the closed cap to open the valve when the piston reaches one end of its excursion, and to close it when it reaches the other end of its excursion.

14. The combination with a cylinder and piston slidable therein of a closed cap for one end of the cylinder, a cap at the other end of the cylinder, and a piston rod extending out through it, means for exerting a pressure upon the piston, a valve in the piston normally closed, a closed chamber within the piston inclosing said valve, a valve stem extending through the entire length of the piston, and projecting at either end, said valve stem adapted to en-

gage the cap at one end of the cylinder to open the valve when the piston reaches that end of its excursion, and adapted to engage the cap at the other end of the cylinder to close the valve when the piston reaches that end of its excursion.

5 In testimony whereof I affix my signature

in the presence of two witnesses this 10th day of November, 1916.
